ENVELOPE

Burt J. Steele, Columbus, Ohio

Application November 21, 1936, Serial No. 112,090

3 Claims. (Cl. 229—76)

This invention relates to envelopes and more particularly to envelopes that are designed to contain mail matter that must be subject to the inspection of the postal authorities if it is to be transported at a special rate lower than the first class rate, said first class rate being for matter not subject to inspection by the authorities.

A number of envelopes for the transportation of printed matter, such as catalogues, pamphlets, leaflets, circulars or the like in which the flaps have been held by means of metal or paper clips, buttons and the like have been proposed or employed but all of these, so far as I am informed, have involved heavy expense in manufacture and handling, and trouble and annoyances in their use.

An object of my invention is to provide an envelope of paper or other suitable material, said envelope being of extreme simplicity of construction, low cost of manufacture, effectual in the security of the contents, and ease in filling and removal or inspection of such contents. Other objects and advantages will appear from the disclosure herein.

The invention is embodied in the example herein shown and described, the feature of novelty being finally claimed.

In the accompanying drawing—

Figure 1 is a view in rear elevation of an envelope according to my invention.

Fig. 2 is a vertical sectional view on, say, the line II—II, Fig. 1, looking to the right, showing the envelope with a content and the two flaps down in content securing position.

Fig. 3 is a fragmentary view of a modification illustrating how the securing flaps can be on opposed walls of the envelope.

Fig. 4 is a fragmentary vertical sectional view on, say, the line III—III, Fig. 3, looking to the right and showing the modified form with a content and the two flaps down.

Referring first to Figs. 1 and 2 the character 5 designates the body of the envelope with adhered lapping portions on lines 6 and 7 leaving one open end throughout the length thereof and that end having upon the edge of the front wall or address side of the body two flaps 8 and 9 projecting therefrom. The said flaps are shown as separated from each other by a V-cut 12 extending preferably to the edge of the said wall so as to be freely movable independently of each other.

The flap 8 is the longer horizontally and is to left ungummed while the narrower flap 9 is to be gummed as suggested at 13. The narrower flap 9 is made of such width that when bent down

and adhered to the rear wall of the envelope, as shown in Figs. 1 and 2 it will so far restrict or narrow the opening left as to preclude the accidental escape of the content of the envelope but permit ample inspection of such content. 5

Referring now to Figs. 3 and 4 the envelope 5^a is shown as having the smaller flap 9^a on the wall of the envelope opposite that containing the securing flap 8^a. In this instance the smaller flap 9^a may also be gummed and the larger flap 8^a left ungummed. 10

The small flap in either form of the envelope is preferably made sufficiently narrow so that when secured a flexible content of the envelope can be entirely withdrawn if desired by first 15 flexing the content within the envelope, but said flap made sufficiently wide to serve as a stop to prevent accidental escape of the content in the ordinary handling by the postal authorities. However the wider flap supplements the content 20 retaining effect and contributes to the prevention of loss of the content in handling in transit.

It is obvious that by means of a suitable cutting die the blank for either form of the envelope can be economically cut in large quantities and 25 such blanks folded and gummed with suitable machinery to make the finished product.

In practice with either form the catalogue, pamphlet or other piece of mail matter 10 to be transported is inserted in the envelope and the 30 larger flap 8 or 8^a turned into the envelope to lie over an end of the article 10 and finally the smaller gummed flap, 9 or 9^a, according to the form used moistened and pressed down on the outer edge of the opposite wall of the envelope. 35

The forms and dimensions of the parts can be changed or parts omitted without departing from the gist of the invention as claimed.

What I claim is:

1. An envelope for the mailing of matter subject to official inspection, said envelope having an opening throughout one of its edges, a relatively narrow flap connected with a wall of said envelope at one end of the said opening, said narrow flap having an adhesive thereon for securing it to the opposite wall of the envelope to restrain accidental escape of its contents, and a supplemental flap connected with a wall of the envelope at said opening, said supplemental flap being laterally disposed in respect to said narrow flap and in operative relation to the other end of said opening, said supplemental flap being freely adapted for insertion into and removal from said envelope, whereby mailable matter substantially filling said envelope is primarily and, before the 55

- adhesion of said narrow flap, easily and quickly insertible into said envelope without flexion and easily removable from said envelope by flexion for official inspection.
- 5 2. An envelope for the mailing of matter subject to official inspection, said envelope having an opening throughout one of its edges, a relatively narrow flap connected with a wall of said envelope at one end of the said opening, said narrow flap having an adhesive thereon for securing it to the opposite wall of the envelope to restrain accidental escape of its contents, and a supplemental flap connected with the same wall of the envelope at said opening, said supplemental flap 10 being laterally disposed in respect to said narrow flap and in operative relation to the other end of said opening, said supplemental flap being freely adapted for insertion into and removal from said envelope, whereby mailable matter substantially filling said envelope is primarily and before the adhesion of said narrow flap, easily and quickly insertible into said envelope without flexion and easily removable from said envelope by flexion for official inspection.
- 15 3. An envelope for the mailing of matter subject to official inspection, said envelope having an opening throughout one of its edges, a relatively narrow flap connected with a wall of said envelope at one end of the said opening, said narrow flap having an adhesive thereon for securing it to the opposite wall of the envelope to restrain accidental escape of its contents, and a supplemental flap connected with a wall of the envelope at said opening, said supplemental flap 10 being of a width substantially equal to the length of said opening beyond said narrow flap and laterally disposed in respect to said narrow flap and in operative relation to the other end of said opening, said supplemental flap being freely 15 adapted for insertion into and removal from said envelope, whereby mailable matter substantially filling said envelope is primarily and before the adhesion of said narrow flap, easily and quickly insertible into said envelope without flexion and 20 easily removable from said envelope by flexion for official inspection.
